UNITED STATES PATENT OFFICE.

ATHERTON D. CONVERSE, OF WINCHESTER, MASSACHUSETTS, ASSIGNOR TO MORTON E. CONVERSE & SON CO., OF WINCHESTER, MASSACHUSETTS, A CORPORATION OF MASSACHUSETTS.

FOLDING TABLE.

Application filed August 21, 1925. Serial No. 51,585.

My present invention relates to improvements in tables having folding legs, such for example as those that are extensively used for card tables, sewing tables, and the like, 5 and aims to provide a very simple construction capable of being manufactured at an extremely low cost, and one in which when the legs are unfolded, they will be rigidly connected in place without the necessity of resorting to the customary braces.

With these objects in view, the invention includes the novel features of construction hereinafter described and defined by the appended claims.

15 In the accompanying drawings:

Figure 1 is a side elevation showing a portion of a table, one corner, with the leg attached thereto by means of my improved construction, the leg being in table top supporting position and with connecting parts shown in dotted lines.

Fig. 2 is a bottom plan view.

Fig. 3 is a section on line 3—3 of Fig. 2.

20 Fig. 4 is a bottom plan view of a modified 25 form of leg attaching means.

Fig. 5 is a detail with the plate of Fig. 4 removed.

Fig. 6 is a perspective detail of the plate, and

30 Fig. 7 is a perspective detail of the supporting means lying beneath the plate.

Referring by reference characters to this drawing, the numeral 1 designates the table top, which may be of any desired material.

35 As such tables are usually constructed of heavy paste board or light wood, I will describe the present embodiment as made of such material, in which event the top is customarily reinforced at its margin by strips

40 2, which may be of any desired finish or ornamentation. In the corner where these meet, I secure a block 3, which is provided with a slot 3^a extending lengthwise of the table, or in the direction in which the leg

45 is desired to fold. Located within this slot is a leg connecting member 4, the end lying within the slot being provided with an eye 4^a which receives a pivot pin 5, which pivotally supports the member 4 in the slot so

50 that it is capable of freely swinging therein in a plane perpendicular to the plane of the table. The outer end of the member 4 is threaded and enters an axial recess in the

end of the table leg, with which it has a screw threaded connection.

55 I may provide the leg 6 with a transverse recess 6^a intersecting the bore into which recess is inserted a nut 7 which is engaged by the screw threads of the member 4.

It will thus be seen that by a rotary motion of the leg it may be screwed on and unscrewed from the member 4. When partially unscrewed from the member 4 the leg may be swung from its folded position in Fig. 2, to the perpendicular position of Fig. 1, whereupon by rotating in a clockwise direction it may be screwed onto the member 4 until the rotation is stopped by the frictional engagement of its end with the under face of the member 3, at which time the leg will be held rigidly attached to the table. When it is desired to fold the leg it is only necessary to partially unscrew the leg by a counter-clockwise rotation, and then swing it down into folded position against the under side of the table top.

70 Of course in a metal leg, the threads could be cut directly in the end of the leg instead of inserting a nut.

75 In order to reduce the amount of rotary motion necessary to lock and unlock the leg, I preferably round the surface of the part 3, as indicated at 3^b.

80 In a modified form of my invention I may use a leg connecting member as shown at 7, having a right angular bend therein, one leg of the part 7 being screwed directly into the reinforcing strip 2. The other leg of the part 7 is screwed into the leg proper 6 as above described.

85 In order to reinforce the leg connecting member 7^a I provide a U-shaped element 8 secured to one of the strips 2 and having a cut away portion 9 therein straddling the member 7 and hugging the angle of the bend.

90 On top of this element 8 I provide a plate 9 also screwed or otherwise fastened to the strip 2 and upon which the top of the U-shaped element 8 bears. A slot 10 in the plate 9 is provided to receive one leg of the member 7 and limits the opening action of the leg 6.

95 Extending outwardly and diagonally from the U-shaped element 8 is an extension 11 adapted to enter a slot 12 in a diagonal strip 13. The strip serves to reinforce the light

top 1 and at the same time provides a rigid support for the **U**-shaped element 8.

It will be apparent that the leg 6 may be swung from its position adjacent the top 1 and strip 2 to an upright one in which the member 7 enters the slot 10. In this position the leg 6 may be rotated clockwise as before until the end thereof frictionally engages the surface of the plate 9.

Such a construction distributes the pull or strain on the leg 6 between the strips 2, plate 9, **U** member 8 and diagonal strip 13. At the same time no strain occurs at the point where the member 7 enters the strip 2, so there is no tendency to bend at this point.

I claim:

1. A folding table including a top, reinforcing strips secured thereto, a leg connecting element pivoted to one of said strips, a member secured to said strips and having a slot therein, said leg connecting element being movable in said slot, and a table leg secured to said leg connecting element and movable therewith, said leg connecting element being right angular, one leg thereof engaging a reinforcing strip, the other engaging the table leg, and a **U**-shaped member secured to a reinforcing strip and having

a portion straddling the leg connecting element.

2. A folding table including a top, reinforcing strips secured thereto, a leg connecting element pivoted to one of said strips, a leg carried thereby, a slotted member secured to said strips, said leg connecting element being movable in said slot, a member straddling said leg connecting member and a diagonal support for said table top, said straddling member engaging said diagonal support.

3. A folding table comprising a top, marginal frame strips forming a corner, a slotted element secured to a strip adjacent said corner, a leg connecting member pivotally secured in said table, said member having a shank lying in said slot when the leg is in normal upright position, said member having a threaded shank adjustably engaging said leg, one end face of said leg abutting the slotted element when the leg is in upright position, said leg being capable of being backed off of the connecting member, swung on its pivot and folded against the table top.

In testimony whereof, I affix my signature.

ATHERTON D. CONVERSE.
